ADOLF MESSER, OF FRANKFORT-ON-THE-MAIN, GERMANY

SEPARATION OF AIR INTO OXYGEN AND NITROGEN BY LIQUEFACTION

Application filed October 27, 1927, Serial No. 228,987, and in Germany November 15, 1926.

This invention relates to the separation of air into oxygen and nitrogen by air liquefaction and separation devices with several air-separation operations—e. g. double column apparatus—which are adapted to produce simultaneously pure oxygen and pure nitrogen. All the temperatures appearing in this specification will be given in degrees centigrade. The temperatures of the gases coming off are, under atmospheric pressure, -195° for nitrogen and -182° for oxygen. The gases at these temperatures enter the heat interchanger where they are used for cooling the compressed air to be used in the process. In the column of the first pressure stage, which is at a fairly high pressure (about 5 atmospheres) above atmospheric, there is located the container for the crude oxygen bath which consists of about 50% of oxygen and 50% nitrogen. The boiling point of this crude oxygen is about -167° at a pressure above atmospheric of 5 atmospheres. In the container for the crude oxygen there is located a heating coil conveying compressed air for evaporating the crude oxygen or maintaining the temperature necessary for its evaporation. When the air passing through the heating coil—especially in the portion of the cooling process during which it is under a pressure of about 200 atmospheres above atmospheric—is super-cooled by the very low temperature of the gases coming off (-195° and -182°), as happens especially in the case of well constructed heat interchangers, there may result such a super-cooling of the compressed air flowing through the heating coil as to cause evaporation in the crude oxygen bath to cease. However, if this is the case—i. e., if the heating coil no longer imparts sufficient heat to the crude oxygen bath—the separating column arranged above the latter fails on account of lack of vapour and consequently the oxygen content of this bath diminishes, as is evidenced by the purity and quantity of the oxygen issuing from the column.

The object of the invention is the removal of the above mentioned causes that lead to the super-cooling of the air and consequently of the crude oxygen bath in apparatus of the

aforesaid type, and according thereto the gaseous nitrogen issuing from the top of the double column is warmed by the liquid crude oxygen obtained in the first pressure stage before it reaches the compressed air in counter-current. 55

In carrying out the invention, there are conducted, in counter-current to the gaseous nitrogen issuing from the upper column of the second pressure stage (low pressure portion), on the one hand liquid crude oxygen from the bath of the column of the first pressure stage and on the other hand liquid washing nitrogen from the latter in such a manner as to bring the issuing nitrogen to a fairly high temperature. Further to the same end, the warmer pure oxygen obtained can be conducted to the colder nitrogen. The nitrogen warmed in this way reaches the heat interchanged for compressed air in such a warm condition that the temperature of the latter as it enters the heating coil located in the crude oxygen bath cannot be lower than the boiling point of the bath. 70

A further important advantage of super-cooling both liquids by the cold gaseous nitrogen lies in the fact that they can be cooled before the pressure-reduction valves to a temperature that is nearly equal to that behind the pressure-reduction valves. Consequently, the different temperatures which would otherwise obtain before and behind the pressure-reduction valves are equalized. By this means, smaller losses of vapour occur after pressure reduction. 75

The above mentioned heat interchange between the compressed air and the gases obtained therefrom is almost perfect. By its means there is effected a saving in the loss of cold and consequently in the expense of the air separation. 80

The process has, finally, the further considerable advantage that in carrying it out a smaller total difference of temperature has to be removed in the heat interchanger than would otherwise be the case and these temperatures can be completely equalized, so that a considerably smaller working pressure is attained. 85

The process will be more fully explained 100

with reference to the apparatus for carrying it out which is diagrammatically represented in the accompanying drawing.

At one side of the two-column apparatus A, B of known construction there is arranged an auxiliary heat interchanger in the tube C which is connected at the top with the column of the second pressure stage B by means of a pipe E for conducting the gaseous nitrogen 10 from the said column. In the tube C there are three coils. The coil 1 (hatched horizontally for the sake of clearness) conducts the liquid crude oxygen from the foot F of the column of the first pressure stage A and 15 brings it to the pressure-reduction valve H of the second pressure stage B. The coil 2 (hatched vertically for the sake of clearness) conducts the liquid washing nitrogen under the condenser K from the first pressure stage 20 to the pressure-reduction valve J of the second pressure stage. In this way there is obtained the result that in the auxiliary heat interchanger approximately the same temperature prevails in each zone as in the corresponding zone of the two-column apparatus 25 A, B.

In double column devices in which the heat of evaporation of the liquid pure oxygen is utilized for the condensation of nitrogen, 30 there is obtained by means of the present invention an increase of temperature and evaporation of the pure oxygen. By conducting this warmed pure oxygen into the auxiliary heat interchanger C it can likewise be used 35 for warming the issuing nitrogen. This case is represented in the drawing, the liquid pure oxygen being taken off at the bottom of the condenser K and led by the coil 3 through the auxiliary heat interchanger C. In this case, 40 the outflow tube 3a of the coil 3 is passed through the nitrogen exit pipe 4 so that the two gases enter the heat interchanger for the compressed air at absolutely the same temperature.

45 The usual heat interchanger for the compressed air and for the gases obtained therefrom remains unchanged in its construction, but its operation is considerably improved by connecting thereto the auxiliary heat interchanger.

50 What I claim is:—

1. Apparatus for preventing the super-cooling of the crude oxygen bath heated by compressed air in the lower portion of a two-column air liquefaction and separation device, comprising an auxiliary heat interchanger, means for conveying into said auxiliary heat interchanger gaseous nitrogen issuing from the top of the double-column of 55 said liquefaction and separation device, means within said heat interchanger for conducting, in counter-current to said gaseous nitrogen, liquid crude oxygen obtained in the first pressure stage of said liquefaction and separation device, and means for conducting 60

the warmed gaseous nitrogen for counter-current to cool the compressed air.

2. Apparatus for preventing the super-cooling of the crude oxygen bath heated by compressed air in the lower portion of a two-column air liquefaction and separation device, comprising an auxiliary heat exchanger, means for conveying into said auxiliary heat interchanger gaseous nitrogen issuing from the top of the double-column of 70 said liquefaction and separation device, means within said heat interchanger for conducting, in counter-current to said gaseous nitrogen, liquid crude oxygen obtained in the first pressure stage of said liquefaction and separation device, means within said heat interchanger for conducting, in counter-current to said gaseous nitrogen, liquid nitrogen obtained in the first pressure stage, and means for conducting the warmed gaseous nitrogen 75 for counter-current to cool the compressed air.

3. Apparatus for preventing the super-cooling of the crude oxygen bath heated by compressed air in the lower portion of a two-column air liquefaction and separation device, comprising an auxiliary heat interchanger, means for conveying into said auxiliary heat interchanger gaseous nitrogen issuing from the top of the double-column 90 of said liquefaction and separation device, means within said heat interchanger for conducting, in counter-current to said gaseous nitrogen, liquid crude oxygen obtained in the first pressure stage of said liquefaction 95 and separation device, and means for conducting the finished oxygen and warmed gaseous nitrogen in thermal contact with each other to the compressed air.

4. Apparatus for preventing the super-cooling of the crude oxygen bath heated by compressed air in the lower portion of a two-column air liquefaction and separation device, comprising an auxiliary heat interchanger, means for conveying into said auxiliary heat interchanger gaseous nitrogen issuing from the top of the double-column of 100 said liquefaction and separation device, means within said heat interchanger for conducting, in counter-current to said gaseous nitrogen, liquid crude oxygen obtained in the first pressure stage of said liquefaction 105 and separation device, and means for conducting the finished oxygen and warmed gaseous nitrogen in thermal contact with each other to the compressed air.

5. The combination with a two column air liquefying and separating apparatus, of a heat interchanger of the countercurrent type having means for conveying through said heat interchanger in one direction the gaseou 110

5 nitrogen from the top of the lower pressure column of said apparatus, and means for conveying through said heat interchanger in the opposite direction crude liquid oxygen from the bottom of the higher pressure column to the lower pressure column intermediate of the ends of the latter.

6. The combination with a two column air liquefying and separating apparatus, of a heat interchanger of the countercurrent type 10 having means for conveying through said heat interchanger in one direction the gaseous nitrogen from the top of the lower pressure column of said apparatus, and means for conveying through said heat interchanger in the opposite direction condensate from the 15 upper end of the higher pressure column to the upper end of the lower pressure column.

7. The combination with a two column air liquefying and separating apparatus, of a heat interchanger of the countercurrent type having means for conveying through said heat interchanger in one direction the gaseous nitrogen from the top of the lower 20 pressure column of said apparatus, means for conveying through said heat interchanger in the opposite direction crude liquid oxygen from the bottom of the higher pressure column to the lower pressure column intermediate of the ends of the latter, and means for conveying through said heat interchanger in the last mentioned direction condensate from the upper end of the higher 25 pressure column to the upper end of the lower pressure column.

30 In testimony whereof I have signed my name this 27th day of September, 1927.
